J. R. ROSE AND EDWARD L. CALEY, JR., OF PHILADELPHIA, PENNSYLVANIA,
ASSIGNORS TO WILLIAM E. WOOD & CO., OF BALTIMORE, MARYLAND.

Design No. 3,765, dated November 23, 1869.

DESIGN FOR A FIRE-PLACE STOVE.

The Schedule referred to in these Letters Patent and making part of the same

We, J. R. ROSE and EDWARD L. CALEY, Jr., of the city of Philadelphia, in the State of Pennsylvania, have invented and produced a new and original Design for a Fire-Place Stove, of which the following is a specification.

The nature of our design is fully represented in the accompanying photographic illustration, to which reference is made, with the exception, however, of the ornamental border-frame A B C, which arches over the right and left sides, and the upper end of the said

stove, as the said frame is the subject of a separate application for a patent.

Claim.
We claim, as our invention, the design for a fire-place stove, as shown and specified.
